AMOS CALLESON, OF BROOKLYN, NEW YORK, ASSIGNOR TO ADRIANCE MACHINE WORKS, INC., OF BROOKLYN, NEW YORK, A CORPORATION OF NEW YORK.

DWELL-MOTION MECHANISM.

1,264,269.

Specification of Letters Patent. Patented Apr. 30, 1918.

Original application filed March 30, 1916, Serial No. 87,805. Divided and this application filed March 30, 1917. Serial No. 158,578.

To all whom it may concern:

Be it known that I, AMOS CALLESON, a citizen of the United States, residing at Brooklyn, in the county of Kings and State 5 of New York, have invented certain new and useful Improvements in Dwell-Motion Mechanisms, of which the following is a specification.

This application constitutes a division of 10 my application for patent for a bottle filling and sealing machine filed March 30, 1916, Serial No. 87,805. The present invention is a novel dwell-motion mechanism designed especially with a view to produce dwells of 15 variable extent. It is herein illustrated in connection with a bottle filling and sealing machine, in which instance it is useful to afford pauses of varying duration so that the machine may be adapted to fill bottles of 20 different sizes; but it may be used in connection with any machine in the cycle of operation of which a dwell is desired.

In the accompanying drawings,

Figure 1 is a side elevation, partly in section, of a bottle sealing machine containing the improved dwell motion mechanism;

Fig. 2 is a horizontal sectional view on approximately the line 2—2 of Fig. 1;

Figs. 3 and 4 are views respectively showing the lever 134 in plan and in side elevation;

Figs. 5, 6 and 7 are side and opposite peripheral elevations of the driving member of the said mechanism;

Figs. 8 and 9 are side elevations of cams included in the driven member of such mechanism;

Figs. 10^a, 10^b and 10^c respectively show in end elevation, side elevation and plan the 40 bolt 139;

Figs. 11 and 12 are a side elevation and a plan, partly in section, of a modification of said mechanism; and,

Fig. 13 shows the controller 159^a in side elevation; and Fig. 14 further illustrates said modification, certain parts appearing in section, as in Fig. 12, and others in plan, partly broken away.

In the bottle filling and sealing machine 50 herein used for illustrating one adaptation of my invention the bottles are advanced step by step, on a rotary turret *a*, to position beneath a filling and sealing head *b* which is carried by a suitable structure *c*

arranged to reciprocate, vertically, over the 55 turret *a*, sliding in ways suitably formed at the front of a housing *d*.

This machine, which is fully described in my application hereinbefore designated, is adapted to fill and seal bottles varying in capacity, for example, one-fourth pints, one-half pints, pints and quarts, which of course involves filling periods that vary more or less as these quantities vary. Instead of slowing down or speeding up the machine 60 according as the filling period of the run of bottles to be filled is long or short, *i. e.*, according as the bottles to be filled are large or small, the speed of the machine remains the same whatever the length of the filling 65 period, but each cycle of the operations on a bottle is interrupted by a dwell which is variable, *i. e.*, according to the length of the filling period appertaining to the particular run of bottles to be handled. For example, 70 so far as the structure *c* in the machine herein shown is concerned, each full cycle— involving downward movement to bring the sealing head and bottle head into cooperative relation for sealing and apply the 75 closure and then an upward or recovery movement—is interrupted during the downward movement by a dwell commensurate in extent with that of the filling period for the particular size of bottles being handled and 80 occurring between the bringing of the bottle and sealing head together and the closure applying operation. Describing the present invention, now, with reference to the actuation 85 of the structure *c* by way of example:

The drive shaft 123 (Figs. 1 and 2) is equipped with a worm 124 meshing with the worm portion 125 of a rotary member including a clutch 126 freely revoluble on a transverse shaft 127. Shafts 123 and 127 90 are journaled in the housing *d*. Fixed on the shaft 127 are the following elements: a clutch member 130, spaced peripheral cams 131 and a barrel cam 132. On a shaft 133 mounted in the housing below and parallel 95 with shaft 127 is fulcrumed a two-armed lever 134 which is oscillated by the coaction of the two cams 131, having rollers 134^a bearing thereon and a fork 134^b (Figs. 3 and 4) engaging the structure *c*. In suitable 100 bearings in the housing *b* is journaled a vertical shaft 135 which, when oscillated, operates through means not shown to advance 105

the turret *a* step by step to position the bottles successively under the structure *c*, or main slide, the same having a crank 138 equipped with a roller 138^a (Fig. 2) engaging in the groove of the barrel cam 132.

Assuming the shaft 127 to be rotated at constant speed, the relation of the cam 132 to the cams 131 is such that when the latter elevate the main slide the former causes the 10 turret to advance one step to position a bottle under the sealing head *b*. The cams 131 are formed with opposite neutral or concentric portions 131^a (Figs. 8 and 9) which cause a dwell in the descent of the main 15 slide that is sufficient to permit the filling (through the head *b*) of bottles having the smallest capacity-standard, *i. e.*, one-fourth pints. For filling bottles of greater capacity-standard the said dwell in the present 20 machine is increased by bringing to a standstill the shaft 127 (and the other elements on said shaft which actuate the moving parts of the machine) to which the cams 131 are fixed. This is accomplished, in a way 25 to permit the dwell to be of variable extent, as follows: Clutch member 130 (which in the present instance is formed integral with the left-hand cam 131, (Fig. 2) contains a latch 139 movable parallel with shaft 127 30 and normally pressed by a spring 140 contained in the housing 141 (Fig. 8) for the latch toward and into engagement with the adjoining face of clutch member 126, which has segmental pockets that are somewhat 35 shallower at 142 than they are at 143 (Fig. 5). According as a latch retractor in the form of a knife 144 pivoted at 145 on a horizontal axis parallel with the shaft 127 (Figs. 1 and 2) is shifted into or out of the path 40 of a beveled face 139^a on the latch, so, assuming the latch to be locking the clutch members 126 and 130 together, it will withdraw the latch when it sweeps around (thus unlocking the clutch members), or leave it 45 undisturbed. On a platform 78 of the housing and suitably retained in place by a cover plate 146 (Figs. 2 and 11) is arranged to slide parallel with the shaft 127 a block 147; its sliding movement may be effected 50 by the manually operated screw 148 swiveled in the housing and having its threading engaged with the block and provided with a handle 148^a. It carries a dog 149 spring-pressed against the periphery of the clutch 55 member 126 and having freely penetrating it a laterally projecting pin 150 on the retractor 144. At its left side the periphery of the clutch member 126 is continuous or circular, as at 126^a; but the remainder of its 60 periphery, somewhat reduced in diameter, has in the present case two diametrically opposite projections 126^b extending each one-third of the distance toward the right side of the clutch member and two other 65 diametrically opposite projections 126^c and

126^d (each 90° from each projection 126^b); the former of which extends two-thirds of said distance and the latter clear to the right hand side of said member. When the dog is arranged so as to bear on surface 126^c the 70 knife will be held back, and clutch member 130, being therefore locked to clutch member 126 will, as also shaft 127 and all the mechanisms driven therefrom, be driven thereby, the dwell which occurs in this case 75 being only that produced by the cam surfaces 131^a. On shifting the dog the next stage to the right the dwell due to cam-surfaces 131^a will be augmented by a dwell due to actual stopping of the clutch member 130 and consequently shaft 127 and all parts operated from it, thus: The retraction of the latch is caused by its sweeping around against the knife when the latter is in the retracting position; and always, though the 80 knife immediately be returned to that position after withdrawal to release the latch (to allow it to lock clutch member 130 to clutch member 126), the locked members must make one complete revolution before 85 retraction can be again effected by the knife. In the position of lateral adjustment of the dog now assumed, the clutch member 130 will complete a cycle with clutch member 126 and come to a dwell, the knife being 90 in latch-retracting position because at the end of the revolution the dog is not on a projection but on a low portion of the periphery of clutch member 126; in this the dog will have been repressed (withdrawing 95 the knife) four times by the four projections (but, each time without effect on the latch, of course, because it is out of position to engage the knife). But on the repositioning of the dog next ensuing after inception of the dwell and consequent release of the latch the latter will enter that pocket 142-143 of clutch member 126 which happens to be opposite, locking the clutch members together for another complete cycle. 100 The pockets are equally spaced and four in number, so that after four idle impulses have been imparted to the knife by the projections and then, the latch being unlocked, the fifth impulse occurs and the latch consequently resumes locking position, a dwell of a one-quarter revolution has occurred. On shifting the dog to the next stage the 105 operation is the same, except that since in this case only two projections 126^b and 126^c are operative the dwells are equal to one-half a revolution. On shifting the dog to the next stage the operation is again the same, but results in dwells equal to a full revolution. In all cases, as stated, one complete revolution of clutch member 130 (and all parts driven therefrom) intervenes between dwells due to retraction of the latch. Thus, the machine is adapted, by manipulating screw 148, for the filling of, for in- 110 115 120 125 130

stance, bottles of the half-pint, pint and quart sizes, for example.

In Figs. 11 to 14 a modification of the mechanism is shown adapted to effect dwells not only of $\frac{1}{4}$, $\frac{1}{2}$ and 1 full revolution (for half pints, pints and quarts), but of $\frac{1}{4}$, $\frac{1}{2}$, and 2 full revolutions (for one and one-quarter, one and one-half and two quart bottles). Here the worm wheel 151 has secured thereon by screws, a clutch 152 having pockets 153 like the pockets of clutch 126 already described; part 152 retains in place a ring 154 revoluble thereon. 151, 152 and 154 correspond to the member including the worm-wheel 125 and clutch 126 already described, being likewise revoluble on shaft 127; but in this case, as described above, the peripheral part (154), which has the peripheral continuous surface 154^a and projections 154^b like those of clutch member 131, is revolvable independently of the rest. The other clutch member, 155, is identical to clutch member 130, being fast on the shaft and carrying the spring-pressed latch 156, corresponding in every respect to latch 139.

Movable in member 151-152 parallel with shaft 127 is a latch 157 having its right-hand end engageable in a single pocket 158 in the adjoining face of ring 154 and its left-hand end projecting and formed with an inwardly facing notch 157^a whose inner side is formed by a spring-cushioned pin 157^b. This notch receives the continuous exterior flange of the annular portion 159^a, embracing the shaft, of a latch-controller including the thrust-piece 159^b extending parallel with said shaft and slideable in a hole 160 penetrating the bearing 161 for the shaft and adapted to enter a recess or notch 162 in the inner face of a cam 29 (when said notch turns into coincidence therewith) under the pressure of a spring 163 housed in said bearing. Measured in the degrees of a circle, recess 162 is approximately the same distance from latch 156 as knife 144 is from the thrust piece 159^b of the controller. Viewed from the left, shaft 127 rotates clockwise, and the right side of notch 162 is sloping, forming a cam, as at 162^a, Fig. 14.

It will be apparent that if the ring 154 remains locked (by latch 157) to member 151-152, these parts then rotating as one, the operation would be the same as in the filling-time-control mechanism already described, *i. e.*, there would be no augmented dwell, or a dwell of $\frac{1}{4}$ th, $\frac{1}{2}$ or one full revolution, alternating with one full rotation of shaft 132, according as the dog 149 occupied the first, second, third or fourth positions, respectively, from the left with respect to the periphery of ring 154.

Assuming that dwells of $\frac{1}{4}$ revolution are to be produced (dog 149 being arranged to be struck by all four projections on ring

154, and starting at the beginning of a dwell): Recess 162 comes opposite the latch-controller thrust-piece 159^b, which retracts the latch 157 to break the connection between the constantly rotating member 151-152 and ring 154, the latter being however immediately cammed back by surface 162^a of the recess so that the latch (wiping over the face of the ring) will snap into the pocket 158 when member 151-152 has completed a revolution. (Latch 156, moreover, also was withdrawn when latch 157 was withdrawn, because knife 144 is the same number of degrees of a circle from part 159^b of the controller as latch 156 is 80 from recess 162). Having thus completed one idle revolution member 151-152 "picks up" the ring 154, by its latch snapping into pocket 158, and turns it. This turning causes one of the projections on the ring to 85 force back the knife, so that, in the regular way, after a quarter idle revolution, the latch 156 by entering the adjacent pocket in member 155 "picks up" the latter and shaft 132 and causes them (they having now been 90 standing at dwell, while member 151-152 rotated $\frac{1}{4}$ revolution) to rotate until the latch 156 and recess 162 again come around to the knife and controller, *i. e.*, after performing one complete revolution. Thereupon the operation will be repeated, giving alternate dwells and rotations of the shaft respectively equal to $\frac{1}{4}$ and one full revolution of the driver—151-152. The operation will be substantially the same if dog 100 149 is arranged to be struck by one, two or only one of the projections on the ring, excepting that in those cases the idle movement for one revolution of member 151-152 with respect to the ring will give dwells of 105 $\frac{1}{3}$ and 2 revolutions, respectively, alternating with rotations of the shaft 127 each of one revolution.

The dog 149 will of course check the ring 154^b, by engaging one of its projections, 110 after each release of the ring by the latch; but I prefer to provide an auxiliary spring stop 164 to act substantially in the same way and thus insure against the ring being dragged around by friction, or otherwise, 115 with the effect of withdrawing the knife and so causing locking movement of latch 156 prematurely.

Ring 154 may be kept locked to member 151-152 by latch 157 by turning the keeper 120 165 into the full line (Fig. 11) position to prevent the latch-controller moving into recess 162 under pressure of spring 163.

It will be noted that each movement of the main slide *c* is the same, in point of time expended in performing it, whether the machine be adjusted for the filling of large or small bottles; only the intervening pauses are varied, according to the capacity-standard of the run of bottles being handled. A 130

given number of bottles above the minimum size can therefore be handled in the present machine more quickly than in machines heretofore devised, wherein in order to handle 5 bottles varying in capacity standard pauses of the proper extent were obtained by changing the speed of the machine, *i. e.*, so that as the pauses were changed in extent so the time to make each advance was changed, 10 and in the same proportion.

Having thus fully described my invention, what I claim as new and desire to secure by Letters Patent is:—

1. A dwell-motion mechanism including 15 rotary driving and driven members having a releasable connection between them, the former rotating at substantially constant speed, and means to control said connection, the driving member having means extending 20 around its axis to actuate the control means intermittently.
2. A dwell-motion mechanism including 25 rotary driving and driven members having a releasable connection between them, the former rotating at substantially constant speed, and means to control said connection, the driving member having means extending around its axis to actuate the control means 30 at variable intervals.
3. A dwell-motion mechanism including 35 rotary driving and driven members, the former rotating at substantially constant speed, a releasable connection normally interlocking 40 said members, and means to control said connection normally arranged in but movable out of position to release the same, the driving member having means extending around its axis to move the control means 45 out of said position intermittently.
4. A dwell-motion mechanism including 50 rotary driving and driven members, the former rotating at substantially constant speed, a releasable connection normally interlocking said members, and means to control said connection normally arranged in but movable out of position to release the same, the driving member having means extending around its axis to move the control means out of said position at variable intervals.
5. A dwell-motion mechanism including 55 rotary driving and driven members, the for-

mer having a projection or projections, a latch normally interlocking said members, and latch-retracting means normally held in, but engageable by said projection or projections to be thereby moved out of, the path of rotation of the latch.

6. A dwell-motion mechanism including 60 rotary driving and driven members, the former including relatively revoluble parts one rotating at constant speed, a releasable connection normally interlocking said part and the driven member, means to control said connection, the other part of the driving member having means to actuate the control 65 means, and means to releasably interlock said parts.

7. A dwell-motion mechanism including 70 rotary driving and driven members, the former including relatively revoluble parts one rotating at constant speed, a releasable connection normally interlocking said part and the driven member, means, controlled by the driven member, to releasably interlock said parts at intervals.

75 8. A dwell-motion mechanism including rotary driving and driven members, the former including relatively revoluble parts one rotating at constant speed, a releasable connection normally interlocking said part and 80 the driven member, means to control said connection normally arranged in but movable out of position to release the same, the other part of the driving member having means to move the control means out of said 85 position, and means to alternately interlock and release said parts.

9. A dwell-motion mechanism including 90 rotary driving and driven members, the former including relatively revoluble parts one rotating at constant speed, a releasable connection normally interlocking said part and the driven member, means to control said connection normally arranged in but movable out of position to release the same, the 95 other part of the driving member having means to move the control means out of said position, and means, controlled by the driven members, to alternately interlock and release said parts at intervals.

100 In testimony whereof I affix my signature.
AMOS CALLESON.
